50 This invention relates to a switching system and translator therefor. Its principal object is to provide a new and improved switching system wherein the lines are terminated in non-decimal groups, together with a new and improved translator for translating called decimal line numbers into non-decimal line-locational numbers suitable for controlling the extension of connections to called lines.

I. GENERAL DESCRIPTION

55 This application is a division of our prior application for a Primary-Secondary-Spread Crossbar Telephone System, Serial No. 85,292, filed April 4, 1949, now Patent No. 2,674,657, issued April 6, 1954.

As disclosed in the noted parent application, common control apparatus is provided to receive dialed digit information for use in controlling the extension of connections to called lines. Such common control apparatus includes (1) a block controller for generally supervising the extension of connections, (2) a block translator for translating the decimal digit information (hundreds, tens, and units) of the called number into non-decimal digit information (frame, primary, fives, and units) identifying the physical location of the called line, and (3) an out-

going controller for controlling the extension of connections to called outgoing trunk groups.

A specific object of the invention is to provide a block translator which is arranged and interconnected to normally effect a fixed decimal-to-non-decimal translation of the line digits of called line numbers according to the normal physical location of any called line and which is further arranged to set aside the fixed translation, when required, and substitute an overriding translation therefor for extending a connection to the line at a different location.

An important feature related to the last stated object is that the output conductors (primary, fives, and units) of the translator are used in combination, thereby reducing the number of relays and relay contacts required in the translator.

A further feature is that the noted overriding translation operation permits the continued use of line numbers assigned to lines terminated at changed locations thereby enabling traffic unbalance among certain line primary switches to be corrected without changing line numbers. Service according to this feature is referred to herein as number-transfer service.

Another feature arising from the provision of the overriding translation operation resides in the arrangement providing common-number (or P.B.X) groups of lines as desired. The translator upon receiving the called number assigned to a common-number group of lines, cancels the normal fixed translation; tests the lines in the common group; selects an idle one of the lines; and sets up an overriding translation number corresponding to the physical location of such selected line to control the extension of the connection thereto. Service according to this feature is referred to herein as common-number service.

A further feature using the overriding translation operation resides in an arrangement for providing intercept service whereby calls to disconnected lines or disconnected stations on party lines are directed to an intercept operator. The translator responds to the calling of the number of a disconnected line or station by cancelling the normal fixed translation and substituting an overriding translation to route the call to an intercept operator. Service according to this feature is referred to as intercept service.

A further feature concerned with providing intercept service resides in an arrangement whereby a group of equivalent intercept trunks is provided and the overriding translation is varied to correspond to a currently idle intercept trunk.

Other objects and features will appear as the description progresses.

IA. The drawings

The accompanying drawings, comprising Figs. 1 to 4 disclose a preferred embodiment of the invention as follows:

Fig. 1 is a single-line block diagram of the apparatus employed in extending connections to and from lines and trunks and showing the relationship existing between the block translator and other apparatus of the disclosed switching system;

Fig. 2 (parts 1 to 4) shows the line-numbering plan of the switching system embodying the invention and the translation plan for the block translator;

Fig. 3 (parts 1 to 8) is a circuit diagram of the relay section of the block translator; and

Fig. 4 (parts 1 to 5) is a circuit and wiring diagram of the pin-terminal section of the block translator.

In Fig. 1, the apparatus of exchange B includes the main distributing frame M.D.F., through which the subscriber lines and the trunks are interconnected with the switchboard apparatus; four line-link frames A, B, C, and D, of which line-link frames A and B are shown at 250A and 250B; a block-link frame shown at 251; and a trunk-coupler frame shown at 252.

In the chosen embodiment of the invention, each of the four line-link frames A to D terminates 250 lines, providing a capacity of 1000 lines for the exchange.

Considering line-link frame A, for example, its function is to connect any calling one of the 250 subscriber lines which it serves with an idle one of a group of originating trunks, such as trunk 203A, and to interconnect any of its terminating trunks, such as 207A, with any called one of the subscriber lines connected with the frame. For this purpose line-link frame A is provided with a number of line-link primary switches 800A and a number of line-link secondary switches 900A. The subscriber lines are brought into the primary switches in the manner shown for calling line 200, which is brought in through jumper 201 on the main distributing frame M.D.F. to its own individual vertical location on line-link primary switch 800A.

The originating trunks extend from respective vertical locations on the line-link secondary switches, such as 20 is shown for originating trunk 203A. The terminating trunks are connected to their own respective vertical locations on the line-link secondary switches, such as is shown for terminating trunk 207A. The line-link primary and secondary switches are interconnected by a suitable number of line links, one of which is shown at 202A.

The apparatus on line-link frame A further includes line-controller apparatus comprising line-controller switches 1000A and 1100A, and line controller 1200A, 30 which are shown in complete circuit diagram in Figs. 10, 11, and 12 of our parent application. The line-controller switches are 1000A and 1100A, and are interconnected with line controller 1200A by a group of control wires 240A.

35 The general purpose of the noted line-controller apparatus is to control the interconnection of lines with trunks through switches 800A and 900A over two-way line links 202A. This general control resides primarily in line controller 1200A.

40 The purpose of the line-controller switches is to interconnect line controller 1200A with any concerned line-link primary switch such as 800A over conductors such as 211A and 212A. Line-link frame B (shown at 250B) contains apparatus similar to that of line-link frame A. The correspondence is shown by employing the letter B as a suffix for each reference character applied at line-link frame B, whereas the letter A is used as a suffix for each reference character applied at line-link frame A.

45 The purpose of the block-link frame, shown at 251, is to extend connections received over incoming trunks such as 2085, and over originating trunks such as 203A, to an idle outgoing trunk such as 2020 in a called group, or over an idle terminating trunk such as 207B to the line-link frame terminating the called line. For this purpose, the block-link frame is provided with a number of block-link primary switches such as 1300 and with a number of block-link secondary switches such as 1400, interconnected by block links 206.

50 The incoming and originating trunks such as 2085 and 203A are required to be suitably coupled to the switchboard apparatus at the block-link frame in order that the necessary digit information as to call destination be recorded and acted upon. This general function is assigned to block couplers 500 individual to the respective incoming and originating trunks. Incoming block coupler 500-I is connected individually with incoming trunk 2085 by jumper 204', while local block coupler 500-L is connected individually with originating trunk 203A through jumper 204. Conductor sets 232 and 205 extend the incoming and originating trunks 2085 and 203A beyond the block couplers to respective vertical locations on block-link primary switches 1300.

55 The outgoing and terminating trunks (such as 2020 and 207B) extend from respective vertical locations on block-link secondary switches 1400.

The specific inter-relation between the block-link primary and secondary switches via the block links is shown in the general trunking diagram, Fig. 3, parts 3, and 4 of our prior application.

General control over the primary and secondary switches on the block-link frame is exercised by block controller 1600. When any connection which has reached a block coupler is ready to be extended, block-controller switch 1500 operates to connect block controller 1600 to the concerned block-link primary switch such as 1300. The calling block coupler is thereupon connected directly with block controller 1600 through conductors in group 221.

If the call being handled is an outgoing call (one to be completed over an outgoing trunk such as 2020) outgoing controller 1700 is called into play over an initial digit wire in group 1D. It is interconnected with the outgoing trunks over respective conductors 227, and is interconnected with the block controller over the conductors in group 241. Its function is to determine which trunks in the called group are idle and to appropriately relay that information to the block controller.

When the connection being handled by the block coupler associated with the block controller is for a called line of the local exchange, hundreds, tens, units, and stations digit information has been stored in the block coupler, and is forwarded to the block translator 1800 over conductor groups H, T, U, and ST.

Block translator 1800 is shown in complete circuit diagram in Fig. 3, which shows the relay section thereof, and in Fig. 4, which shows the pin-terminal section thereof. The general purpose of the block translator is to determine from the dialed digit information which of the four line-link frames A to D terminates the called line, as well as the specific location of the called line on such frame, and to transmit appropriate translated information to the line-controller apparatus on the called line-link frame, according to the location of the called line thereon. This information is transmitted over conductors in the concerned one of groups 223A to 223D.

The line-controller apparatus on the called line-link frame acts according to the information received from the block translator to prepare for the extension of the connection to the specific called line. Among other things, this line-controller apparatus identifies the called line-link frame at block controller 1600, following which the block controller and the line-controller apparatus cooperate in extending a connection to the called line over an idle path. The cooperation between the block controller and the line-controller apparatus on the line-link frames is controlled over respective conductor groups 222A to 222D.

II. GENERAL OPERATION (FIG. 1)

The general operation will now be described with reference to Fig. 1.

IIA. Local calls

If the subscriber at station S1 on line 209 desires to make a local call, such as one to the subscriber at station S2 on the line 210, he removes his receiver, waits for dial tone from a local block coupler; and then dials the directory number of the called station, containing five digits, termed initial, hundreds, tens, units, and stations.

When the receiver is removed at calling station S1, calling line 200 is thereby bridged in the usual manner to operate the usual line relay thereof in exchange B. This results in the operation of line-controller switches 1000A and 1100A to associate line controller 1200A with line-link primary switch 800A at which the calling line terminates. The line links (such as 202A) serving primary switch 800A are thereupon tested by the line controller 1200A over respective conductors 212A, and the associated originating trunks, such as 203A, are tested over respective conductors 213A. From these tests, the line controller matches an idle path for extending the calling line to an idle block coupler, the path over line-

link 202A and originating trunk 203A, for example. When this occurs, the line controller causes primary and secondary switches 800A and 900A to effect a mechanical selection of the matched line link 202A, and energizes conductors 211A and 213A to close the appropriate stackups of contact elements in the primary and secondary switches 800A and 900A to extend the calling line over line link 202A to the local block coupler 500-L, to which originating trunk 203A is connected by jumper 204. Line-controller switches 1000A and 1100A, and line controller 1200A are now returned to common use, leaving the calling line 200 connected to local block coupler 500-L by way of line link 202A and originating trunk 203A.

Upon receiving a dial-tone signal over the established connection, from the block coupler 500-L, the subscriber at calling station S1 operates his usual calling device to transmit impulses representing the five digits in the directory number of called station S2. They comprise an initial digit indexing exchange B, and hundreds, tens, units, and stations digits indexing the called line and the called station S2 thereon. These digits are recorded on respective registers in the block coupler 500-L before any external switchboard action occurs. As soon as the stations digit has been dialed, block-controller switch 1500 associates block-controller 1600 with the primary switch 1300 which serves block coupler 500-L. At the same time, block coupler 500-L is associated with block controller 1600 over the conductors in group 221. Also, at the same time, the dialed hundreds, tens, units, and stations digit information is transmitted to block translator 1800 over the respective conductor groups H, T, U, and ST.

The block translator thereupon determines the line-link frame which serves the called line (line-link frame 250B), and transmits thereto (over conductors in group 223B) translated digit information indicating the primary switch (800B) which serves the called line, and indicating the specific vertical appearance of the called line on that primary switch. When this occurs, line controller 1200B identifies itself at block controller 1600, and exercises a control over conductors in group 240B to cause line-controller switches 1000B and 1100B to position themselves according to the switchboard location of the called line. The line links (such as 202B) serving primary switch 800B are now tested over respective conductors 212B, and the testing information is imparted to block controller 1600 over respective conductors in group 222B. The sleeve conductor 211B of the called line 210, is now extended to block controller 1600 over a conductor in group 222B, enabling the block controller to test the called line to determine its busy or idle condition.

If the called line tests idle, the block controller matches an idle path thereto over a block link such as 206, a terminating trunk such as 207B, and a line link such as 202B. The block links and terminating trunks are tested over respective conductors 225 and 226.

When this available idle path between block coupler 500-L and the called line has been determined, block controller 1600 closes appropriate select-magnet circuits to effect mechanical selection of block link 206 at primary and secondary switches 1300 and 1400, and to effect mechanical selection of line link 202B at switches 900B and 800B. When these selections have been made, block controller 1600 operates through a conductor in group 221 to close the appropriate circuit path through primary switch 1300 to extend the connection to the selected block-link 206; operates over conductor 226 to cause the appropriate connection to be closed in secondary switch 1400 to extend block link 206 to terminating trunk 207B, and to cause that trunk to be extended to the selected line link 202B by switch 900B, and operates, over a conductor in group 222B, and over sleeve conductor 211B, to cause the appropriate connection to be

closed in primary switch 800B to interconnect line link 202B with the called line 210.

Upon the foregoing operations having been completed, local block coupler 500-L begins to apply ringing current to the called line to signal the called station S2 thereon over the established connection across the block-link frame and across the called line-link frame, and the items of common apparatus (block-controller switch 1500, block-controller 1600, block translator 1800, and line-controller apparatus 1000B to 1200B) are promptly returned to common use, leaving the connection intact between the calling and called lines.

When the call has been answered, the subscribers at stations S1 and S2 may converse as described. When both subscribers have replaced their receivers, block coupler 500-L opens front and rear holding circuits which it had previously held closed, whereupon the existing connection is broken at each of the switches 800A, 900A, 1300, 1400, 900B, and 800B.

III. Inter-exchange calls

The operation of the system in extending connections from calling lines in the local exchange to trunk lines extending to other exchanges is as described in our prior application, and includes the operation of outgoing controller 1700, previously referred to.

When exchange B is called from exchange A, the call from exchange A reaches exchange B over an incoming trunk such as that illustrated. This trunk is extended through parts 2082 to 2085 and jumper 204' to incoming block coupler 500-I, similar to the local block coupler except that it preferably does not apply dial tone upon being taken for use.

Following seizure of the incoming block coupler, the call may be extended to exchange C by the dialing of the appropriate initial digit at block coupler 500-I or may be extended to any desired called line of exchange B by dialing the appropriate initial digit, followed by the hundreds, tens, units, and stations digits in the directory number of the called line and station thereon. The connection may be extended from block coupler 500-I to line 200 over conductor group 232 and associated vertical location on primary switch 1300, and thence as hereinbefore described for a call originated at local station S1.

III. NUMBERING AND TRANSLATION PLAN (FIG. 2)

As disclosed in our prior application, there are ten primary switches 800A (Fig. 1) on line-link frame A, each having twenty-five vertical locations, or cross paths, to which twenty-five subscriber lines are respectively connected and each having ten horizontal locations, or longitudinal paths, to which ten line links 202A are respectively connected. Line-link primary switch 800 is termed a 25 x 10 three-wire switch. It accordingly has twenty-five vertical rows of three-wire stackups of contact elements. These rows are termed verticals V1 to V25, respectively. The verticals V1 to V25 are aligned to provide ten horizontal rows, termed horizontals H1 to H10.

Since the 1000 lines served by the line link frames A, B, C, and D are grouped non-decimally on the frame (in groups of 250, 25, and 5), instead of a decimal grouping by hundreds and tens, translation is required to indicate the physical location of the called line for directing the call thereto. This translation requires a frame designation (A, B, C, or D), a primary switch designation (P1 to P10), a fives group designation (F1 to F5), and a units designation (U1 to U5).

The preferred grouping and numbering of lines is shown in Fig. 2, which shows the location of each line 000 to 999 on the frames A to D, together with the translated equivalent of each line number. The correlation between line numbers and translated numbers will be described more fully hereinafter.

Parts 1, 2, 3, and 4 of Fig. 2 refer respectively to line-link frames A, B, C, and D. In each part of the drawings, there are ten horizontal double rows (1 to 10) of numbers. These rows refer respectively to the ten line-link primary switches 800 on the concerned line-link frame. The upper row of numbers of any such horizontal double row comprises the twenty-five line numbers assigned respectively to the lines connected to the verticals V1 to V25 of the primary switch, while the lower row comprises the translated equivalents of the respective line numbers of the upper row.

It will be observed that line numbers 000 to 249 are assigned to the 250 lines served by the ten primary switches 1 to 10 of line-link frame A; line numbers 250 to 499 are assigned to line-link frame B; line numbers 500 to 749 are assigned to line-link frame C; and line numbers 750 to 999 are assigned to line-link frame D; and that the line numbers are applied consecutively from the first vertical V1 of line-link primary switch 1 of line-link frame A to the last vertical V25 of line-link primary switch 10 of line-link frame D. It will be observed further that at any line-link frame the translated numbers run consecutively (by tens, fives, and units) from 111 to 055, being the same 250 translated numbers for any line-link frame. The block translator directs any such translated number to the line-link frame at which the called line terminates, as will be described hereinafter.

IV. BLOCK TRANSLATOR 1800 (FIGS. 3 AND 4)

A detailed description of the invention will now be given with particular reference to Figs. 3 and 4.

The block translator 1800, shown as a rectangle in Fig. 1, as shown in full in Figs. 3 and 4. Fig. 3 (parts 1 to 8) is termed the relay section as it illustrates the portion which includes the relays and associated circuit elements such as resistors. Fig. 4 is termed the terminal-pin section as it illustrates the section of the block translator which comprises blocks, or columns, of insulated terminal pins whereat jumpers may be installed as desired to cause the normal fixed translation for selected called lines or stations to be replaced by overriding translation to direct the concerned calls to desired other line terminals as a part of its operation in providing normal fixed translation above noted.

IV.A. Purpose and function

The block translator has the two general purposes and functions. It directs calls to respective called lines by normal fixed translation, and it provides standard services by setting up "special" translation which overrides the normal fixed translation as above indicated.

IV.A1. Call direction by normal fixed translation

As hereinbefore pointed out, the 1000 lines served by the disclosed apparatus through line-link frames A, B, C, and D are grouped non-decimally on the line-link frames as shown in Fig. 2 and it is the main purpose and function of the block translator to effect the translation as shown by Fig. 2.

On the receipt of the hundreds, tens, and units digits of a called number, the block translator selects the concerned line-link frame and sends to it a translated equivalent number containing translated primary, fives, and units digits respectively identifying the involved primary switch on the called line-link frame, the fives group of lines on the primary switch, and the units location of the called line within the group of five. This translation according to Fig. 2 is referred to as the normal fixed translation.

IV.A2. Standard services by overriding translation

The second purpose and function of the block translator is to direct the performance of standard services which are referred to herein as (1) number-transfer serv-

ice, (2) intercept service, (3) common-number service, and (4) 20-station code-ringing service. The block translator performs any one of these standard services for an assigned called number by setting aside the normal fixed translation in favor of an overriding translation which is effective to direct the call to a preassigned different line location or to an idle line of a preassigned group.

The above standard services are more fully stated as follows:

(1) Number-transfer service, when employed, transfers the call to a new location on any one of the four line-link frames when the switchboard-terminal location of the called line has been altered at the main frame M.D.F. to balance traffic amongst the primary switches, thereby avoiding changing line numbers.

(2) Intercept-service, when employed, transfers the call from a given called line, or from a given station of a multi-station line, to an intercept trunk, leading to an intercept operator.

(3) Common-number service is employed to extend calls for the directory number of a group of lines (such as a P.B.X group) to an idle line of the group.

(4) Twenty-station code-ringing service may be used when the block couplers 500 are modified according to Fig. 22 of our prior application to provide code-ringing service instead of harmonic-ringing service. It is a special case of number-transfer service, and is employed for up to fifty 20-station lines, by connecting the five lines in the fourth fives group of any primary switch on line-link frame A to 20-station service. The corresponding line number from the fifth fives group is assigned to any such line. When the second line number is called, the calling code-ringing block coupler is conditioned by the block translator to alter the ringing code to ring the corresponding station in the second group of ten on the called line.

The normal fixed translation is carried out through permanent wiring interconnecting contacts of the relays of Fig. 3. Overriding translation, when effected for any called number, is carried out through jumper connections between terminal pins shown in Fig. 4. Additional relay apparatus of Fig. 3 not used in the normal fixed translation is thereby brought into play as will be described.

IVB. Functional relay groups

The relays of the block translator comprise separate functional groups as follows:

(1) Translating relays 18D1 and 18D2 are the twenty-station code-ringing group. They have use only when the noted code-ringing block couplers are used, in which case relays 18D1 and 18D2 provide twenty-station code-ringing service for certain lines served by line-link frame A.

(2) Relays 18D3 and 18D4 are the reset group, called into play only when overriding translation is required. They act to cancel the normal fixed translation and to put the indicated overriding translation into effect.

(3) Relays 18E1 to 18E30 are the number-transfer group. When a line has been transferred from one terminal location to another, by a jumper change on the main frame, with no corresponding change in the number of the transferred line, an available one of the relays 18E1 to 18E30 is assigned to that line to effect overriding translation to cause the call to be directed to the new location of the called line rather than to its original location.

(4) Relays 18D5 to 18D14 comprise a ten-relay group allotter. It is called in whenever the number dialed indicates that the call is for a common-number group. It acts to test up to ten lines in the called group to indicate an overriding translation which will direct the call to an idle line of the group.

(5) Relays 18D15, 18D16, and 18D17 control up to ten lines or trunks in a common-number group referred to as P.B.X group 1. Any desired line number in the

1000-line block of numbers may be assigned as the call number to operate these relays to bring the lines of the group into the group allotter for test. Relays 18D18 to 18D20 (not shown) and relays 18D21 to 18D23 are similar three-relay groups assigned respectively to ten-trunk groups identified as P.B.X groups 2 and 3, "P.B.X" being the common abbreviation of private branch exchange.

(6) Relay 18D24 controls up to three lines or trunks in a common-number group referred to as P.B.X group 4. This relay can be operated by any assigned line number to bring the lines of its group into the P.B.X allotter for test. Relays 18D25 to 18D28 (not shown) and relay 18D29 are similar relays respectively controlling three-trunk groups referred to as P.B.X groups 5 to 9.

(7) Relays 18D30 and 18F1 to 18F20 comprise the intercept group. Relays 18F1 to 18F20 are the detector relays assignable to respective lines requiring intercept service. When desired, call-in relay 18D30 is operable directly by any detector relay 18F1 to 18F20, or when desired, its operation is further dependent on a given station on the assigned line being called. When operated, relay 18D30 calls in both relays (18D3 and 18D4) of the reset group to indicate an overriding translation to direct the call to an idle trunk leading to the intercept operator.

(8) Register relays 18A1 to 18A10 and alarm relay 18B11 comprise the hundreds group. One or another of the relays 18A1 to 18A10 operates, depending upon the hundreds digit dialed.

(9) Register relays 18A11 to 18A20 and alarm relay 18B12 comprise the tens group. One or another of the relays 18A11 to 18A20 operates, depending upon the tens digit dialed.

(10) Register relays 18A21 to 18A30 and alarm relay 18B13 comprise the units group. One or another of the relays 18A21 to 18A30 operates, depending upon the units digit dialed.

(11) Register relays 18B1 to 18B10 and alarm relay 18B14 comprise the stations group. One or another of relays 18B1 to 18B10 operates, depending upon the stations digit dialed.

(12) Translating relays 18B15 to 18B16 comprise the 45 fives group. They correspond respectively to the first five lines (0 to 4) in a group of ten, and to the last five lines (5 to 9) therein.

(13) Translator relays 18B23 to 18B26 comprise the 50 25's group. They correspond respectively to the first, second, third, and fourth 25-line groups (00 to 24, 25 to 49, 50 to 74, and 75 to 99) in any hundreds group. They are controlled by the tens register relays 18A11 to 18A20, assisted by fives relays 18B15 and 18B16 when the tens register relay operated is 18A13 or 18A18.

(14) Translating relay 18B27 to 18B30 are the 250's relays, corresponding respectively to line-link frames A, B, C, and D, which in turn (see Fig. 2) correspond to the first, second, third, and fourth 250-line groups (000 to 249, 250 to 499, 500 to 749, and 750 to 999) in the 60 1000-line block. They are controlled by the hundreds register relays 18A1 to 18A10, assisted by the 25's relays 18B23 to 18B26 if hundreds relay 18A3 or hundreds relay 18A8 is operated.

IVC. Terminal-pin blocks

65 The terminal pins of Fig. 4 are shown as small individual circles. They preferably comprise terminal pins passing through blocks or a panel-link insulating member which may be mounted on the rear face of the equipment on which the relay apparatus of Fig. 3 is mounted. These pins provide terminals through which the noted overriding translation is controlled as desired by jumpers extended between the terminals as desired. Each terminal pin preferably extends directly through the rear face of the equipment to provide an exposed inner end

to which a local cable conductor or a strap is attached, and an end exposed on the rear face of the equipment to receive a jumper.

There are 1800 terminal pins shown in Fig. 4. They comprise nine sections (1901 to 1909) of 200 pins each. In any section 1901 to 1909 the pins are arranged in ten columns, with twenty pins in a column, and in twenty levels, with ten pins in a level. For ready identification the twenty levels of pins in a section are divided into four five-level groups 1 to 4. The two hundred pins of a section thus comprise four smaller groups of fifty each.

The nine sections 1901 to 1909 are grouped into the following separate fields according to function, as follows:

Section 1901	Detector field
Sections 1902	
1903	Common field
1904	
Section 1905	Sleeve field
1906	
Sections 1907	Reset field
1908	
1909	

IVC1. The detector field

Section 1901 of the terminal pins comprises the detector field. The first ten levels in this field (groups 1 and 2) are assigned respectively to registered hundreds digits 0 to 9, and terminate hundreds wires H0 to H9.

The one hundred terminals in the last ten levels (groups 3 and 4) of section 1901 correspond respectively to the line numbers in any one of the ten hundreds groups, and terminate one hundred wires 00 to 99.

As hereinafter explained, the running of a two-wire detector jumper such as 1951 from the respective windings of a detector relay to terminals of the detector field corresponding to the three digits of a desired line number energizes both windings of that detector relay only when that line number is registered in the translator.

Connections to terminals in the detector field are made from any set of terminals D1 to D2 in the common field.

IVC2. The common field

Sections 1902 to 1904 of the terminal pins are called the common field because they contain terminals which are to be jumper-connected to the terminals of each of the other fields. The terminals in the common field comprise separate functional groups as follows:

IVC2a. Common-number terminal groups

The first three five-level groups 1 to 3 in section 1902 are assigned respectively to the ten-trunk common-number groups termed P.B.X groups 1 to 3. Each such five-level terminal-pin group provides terminal points for the detector wires D1 and D2 of the assigned P.B.X group, and terminal pins P, F, U, and S (primary, fives, units, and sleeve) for each of the ten lines constituting the respective trunks of the group.

Five-level group 4 in section 1902 accommodates the three-trunk common-number groups termed P.B.X groups 4 to 6 on columns 1 to 3, 4 to 6, and 7 to 9 respectively. Three-trunk groups P.B.X 7 to P.B.X 9 are similarly accommodated by the five-level group 1 of section 1903.

IVC2b. Number-transfer terminal groups

The second, third, and fourth five-level groups (2, 3, and 4) in section 1903 of the common field respectively accommodate wires connected with number-transfer relays 18E1 to 18E10, 18E11 to 18E20, and 18E21 to 18E30 in three groups of ten. Translated-number terminals P, F, and U, and detector terminals D1 and D2 are provided for each number-transfer relay.

IVC2c. Number-intercept terminal groups

The first two five-level groups in section 1904 respectively accommodate wires connected with number-inter-

cept relays 18F1 to 18F10 and number-intercept relays 18F11 to 18F20 in two groups of ten. Station-intercept terminals 1, 2, and 3, and detector terminals D1 and D2, are provided for each number-intercept relay. Level groups 3 and 4 in section 1904 accommodate station-digit wires ST-0 to ST-9, controlled by the station relays of Fig. 3, part 7.

Any terminal 1 to 3 assigned to any intercept relay may be connected (as by jumper 1956) to any desired terminal level in the stations group according to the stations digit in the directory number of a station which has been disconnected from a multi-station line and placed on intercept service. If the called line on intercept service is an individual line, one of the noted terminals 1 to 3 is jumper-connected to ground (as by jumper 1957) which can be found on any terminal pin in level 20 of the sleeve field, section 1905.

IVC3. The sleeve field

The terminal pins comprising section 1905 are referred to as the sleeve field because the first three levels in any five-level group 1 to 4 thereof serve as attachment points for thirty transfer sleeve wires S cabled between the block translator and bunching blocks (not shown) on the corresponding line-link frame A to D. Thirty transfer sleeve wires for each line-link frame make it possible to have as many as thirty lines on any line-link frame serving as trunks in common-number groups. Any such sleeve wire, before use in the translator, is jumpered (on the concerned line-link frame) to the sleeve wire of a desired line location thereon, such as to the terminal from which conductor 211A extends. In Fig. 4, this sleeve wire is jumpered to a desired sleeve terminal S of any desired group P.B.X1 to P.B.X9 in the common field.

The first three sleeve wires S1 to S3 from line-link frame A are permanently wired, through wires in group PJ, for the use of three lines of line-link frame A as a group of three intercept trunks leading to the switchboard of the intercept operator. These lines are numbers 011, 111, and 211. As shown in Fig. 2, part 1, these lines are the second line in the third fives group of primary switches 1, 5, and 9 of line-link frame A. The translated equivalents of these numbers are A132, A532, and A932. If desired, only one or two of these lines are so used, in which case the unrequired sleeve jumpers are omitted on line-link frame A.

IVC3a. Spare levels in sleeve field

In the sleeve field (section 1905), the transfer sleeve wires use only three levels in any group of five, leaving the fourth and fifth levels available for other use.

In group 1 of the sleeve field, levels 4 and 5 terminates wires used in controlling 20-station relay 18D1 depending upon the number dialed and upon the presence of a strap between corresponding contacts of the two levels.

In group 4 of the sleeve field, the contacts in level five are strapped together and grounded to provide ground terminals for the previously noted jumpers relating to intercept service for individual lines.

IVC4. The reset field

The terminal pins in sections 1906 to 1909 are termed the reset field. These sections correspond respectively to line-link frames A, B, C, and D. In the reset field, the terminals in any level are strapped together to provide ten equivalent multiple attachment points for reset jumpers.

In any reset section 1906 to 1909, the first ten levels of terminal pins terminate a multiple of the primary wires (P) outgoing to the associated line-link frame; the next five levels terminate a multiple of the fives wires (F) outgoing to the line-link frame; and the final five levels terminate a multiple of the units wires (U) outgoing to the line-link frame.

The terminals in the reset field receive three-wire reset jumpers (such as 1954) extending from any set of P, F,

and U terminals in sections 1902 and 1903 of the common field.

IVD. Operation for normal fixed translation

Referring particularly to Fig. 3, parts 4 to 8, the operation of the block translator of Figs. 3 and 4 in handling a call requiring only the normal fixed translation will now be described.

Battery normally stands on the upper terminal of each of the hundreds, tens, units, and stations register relays 18A1 to 18A10, 18A11 to 18A20, 18A21 to 18A30, and 18B1 to 18B10. The lower winding terminal of each of these relays serves as the termination point for a digit wire incoming from the block couplers 500. These digit wires comprise hundreds wires H1 to H10, tens wires T1 to T10, units wires U1 to U10, and stations wires ST1 to ST10. Any one of the noted register relays accordingly stands ready to be operated by a marking ground potential on its connected hundreds, tens, units, or stations digit wire.

IVD1. Setting up the dialed number in the translator

As described in our parent application, the hundreds, tens, units, and stations digits dialed into any block coupler 500 for a terminating call are recorded on respective registers HR, TR, UR, and SR in the block coupler 500. When the stations digit has been registered, and if the terminating chain is then idle, the terminating-chain relay 512 in the block coupler in use is operated as described. It connects the block coupler to the block controller 1600 over the terminating-call wires; seizes the terminating chain; and grounds the selected wire in each of the digit groups H, T, U, and ST. The wires thus grounded correspond to the registered hundreds, tens, units, and stations digits.

At the same time, as described in our parent application the associated main terminating-chain relay in section-preference relays 1550 and terminating-start relay 16A6 of the block controller, operate in series with the terminating-chain relay of the seizing block coupler. The block-controller switch is thereby operated to associate the block controller with the block-link primary switch serving the seizing block-coupler section, and the block controller is started into terminating operation.

In the block translator, the noted placing of marking ground on the four register-selected digit wires energizes the corresponding relay in the hundreds group, the tens group, the units group, and the stations group of Fig. 3, parts 4 to 7.

IVD2. Preliminary translation

The ten wires in each of the four sets of digit wires H, T, U, and ST extending from the block couplers 500 to the block translator are considered in the order of from 1 to 10. This is according to the numbering (1 to 9, and 0) of the finger holes on the dial of the usual calling device, and is according to the order in which the impulses are received and registered. But, on the main distributing frame MDF (Fig. 1) and on the line-link frames A, B, C, and D (see Fig. 2), the line numbers are grouped for digit values in the order of from 0, 1, 2, etc., to 9. As shown in Fig. 2, within a group of ten consecutive lines, the directory-number units digits are from 0 to 9; within a hundreds group, the directory-number tens and units digits are from 00 to 99; and in the thousand's group, the directory-number hundreds, tens, and units digits are from 000 to 999. Considering the lines as having ten stations each, the directory-number hundreds, tens, units, and stations digits run from 0000 to 9999.

The noted variance between the order of digits as dialed and the order of digits in the numbering plan of the lines, and stations is taken care of in the translator 1800 by a preliminary internal translating operation within, and local to, each of the four digit groups of wires brought into the translator. For any digit group of wires

75

18A14 or 18A15, if the tens digit is a 3 or a 4.

(H, T, U, and ST), this preliminary translation is a mere rearrangement of the concerned ten-wire group within the translator. The digit-0 wire 10 extends to the first associated register relay (relay 18A1 for the hundreds digit), and the digit-1 to digit-9 wires extend respectively to the second to tenth ones of the associated register relays (18A2 to 18A10 for the hundreds digit). In view of the preliminary translation, the first five register relays in any group of ten correspond respectively to the dialed digits 0 to 4, while the last five register relays in the group correspond respectively to the dialed digits 5 to 9.

IVD3. Operation of the translator relays

- 15 Three sets of translator relays (Fig. 3, part 8) are employed to assist the digit-register relays 18A1 to 18A30 in setting up the translated equivalents of the hundreds, tens, and units digits of line numbers registered thereon. These sets of translator relays are:
- 20 (a) Two fives relays 18B15 and 18B16;
 (b) Four twenty-fives relays 18B23 to 18B26; and
 (c) Four 250's relays 18B27 to 18B30.

IVD3a. Fives translator relays

- 25 The fives translator relays 18B15 and 18B16 are controlled by the units register relays 18A21 to 18A30. If the units digit has any value from 0 to 4, the corresponding one of the units register relays 18A21 to 18A25, through its contacts 12, operates the first fives relay 18B15. If the units digit has any value from 5 to 9, the corresponding register relay 18A26 to 18A30, through its contacts 12, operates the second fives relay 18B16. Relay 18B15 accordingly represents the first five lines (0 to 4) in a decimal group of ten, while relay 18B16 represents the second five lines (5 to 9) in a decimal group of ten.

- 30 The fives translator relays 18B15 and 18B16 enable a decimal group of ten consecutive lines to be split into two groups of five, to facilitate division of the lines of a hundreds group into four groups of twenty-five, and the division of a group of twenty-five into five groups of five, as shown in Fig. 2.

IVD3b. Twenty-fives translator relays

- 45 The four twenty-fives relays 18B23 to 18B26 in the outgoing group respectively represent the four twenty-five line groups of consecutive numbers in any one of the ten hundreds groups of Fig. 2. The twenty-fives relays are controlled by the tens register relays 18A11 to 18A20 jointly with the fives translator relays 18B15 and 18B16.

- 50 If the tens digit is a 0 or a 1, the called line is in the first twenty lines of the hundred, and is therefore within the first twenty-five-line group. Accordingly, the operation of either of the tens register relays 18A11 or 18A12 at its contacts 4 directly operates the first 25's relay 18B23 over wire 1 in group 1835 to indicate that the called line lies in the first group of twenty-five lines within the called hundreds group to which the call is directed.

- 55 When the tens digit is a 2, contacts 4 of the third tens register relay 18A13 ground wire 2 in group 1835 as an indication that the called line is in the third ten-line group within the hundred. Half of this ten-line group lies in the first group of twenty-five and the other half lies in the second such group. If the first fives relay 18B15 is operated, its contacts 6 connect the ground wire 2 of group 1835 to the first 25's relay 18B23, operating it as an indication that the line is in the first group of twenty-five within the hundred. But, if the second fives relay 18B16 is operated, its contacts 6 connect the noted wire 2 to relay 18B24, operating it as an indication that the called line is in the second group of twenty-five within the hundred rather than in the first. The second 25's relay 18B24 is also operated (over wire 3 in group 1835) by contacts 4 of either tens register relay

The third and fourth 25's relay 18B25 and 18B26, are operated by the last five tens relays 18A16 to 18A20 in the same way that relays 18B23 and 18B24 are operated by the first five tens relay 18A11 to 18A15. That is, the first pair and the last pair of these five tens relays operate 25's relays 18B25 and 18B26 respectively, while the intermediate tens relay 18A18 operates relay 18B25 or relay 18B26 depending upon whether the first fives relay 18B15 or the second fives relay 18B16 is operated to close its contacts 7.

IVD3c. 250's translator relays

Translator relays 18B27 to 18B30 correspond respectively to the four 250-line groups into which the numbers within the 1000-line block of numbers are divided as shown in parts 1 to 4 of Fig. 2. Consequently, relays 18B27 to 18B30 correspond respectively to the four 250-line line-link frames A, B, C, and D, to which the 250-line groups are respectively assigned. Relays 18B27 to 18B30 are controlled by contacts 4 of the hundreds register relay 18A1 to 18A10, over the wires in group 1836, jointly with contacts 11 and 12 of twenty-fives relays 18B23 to 18B26.

If the hundreds digit dialed is a 0 or a 1, the corresponding register relay 18A1 or 18A2 grounds conductor 1 in group 1836 to operate the first 250's relay 18B27 as an indication that the called line is within the first 250-line group in the 1000-line block. Similarly, if the hundreds digit dialed is a 3 or a 4, register relay 18A4 or 18A5 is operated to ground conductor 3 in group 1836 to operate the second 250's relay 18B28 as an indication that the call is in the second 250-line group of numbers in the 1000-line block.

If the hundreds digit dialed is a 2, relay 18A13 grounds the associated wire 2 to index the calling of the third hundreds group, which is split between the first and second groups of 250. If the call is for one of the first fifty lines in the hundreds group, the ground on conductor 2 of group 1836 passes through contacts 11 of twenty-fives relay 18B23 or 18B24 to operate the first 250's relay 18B27, but if the line called is within the second fifty-line group within the called hundreds group, the ground on the last noted conductor 2 passes through contacts 11 of relay 18B25 or 18B26 to operate the second 250's relay 18B28.

Similarly, hundreds register relays 18A6 to 18A10, representing the hundreds digits 5 to 9, control 250's relays 18B29 and 18B30, directly for relays 18A6, 18A7, 18A9, and 18A10, and through contacts 12 of the 25's relay 18B23 to 18B26 in the case of relay 18A8, which represents the eighth hundreds group (7) which is split between the third and fourth groups of 250.

IVD4. Translated line numbers

As shown in Fig. 2 each called line number (000 to 999) has an equivalent translated number 111 to 055. The same 250 translated numbers, 111 to 055, appear in the same order for any one of the four line-link frames. Each translated number contains:

- (a) A primary digit from 1 to 0,
- (b) A fives digit from 1 to 5, and
- (c) A units digit from 1 to 5.

The block translator secures the effect of prefixing a line-link-frame designation A, B, C, or D to each of the 250 translated equivalent line numbers 111 to 055 shown on any one of the four parts of Fig. 2. This prefixing effect is secured by transmitting any such line number over the one of four groups of digit wires 1841 to 1844 (part 8 of Fig. 3) which leads to the concerned frame A, B, C, or D. Each such group contains ten primary wires P, five wires F, and five units wires U.

IVD4a. The translated primary digit (1 to 0)

For any line-link frame A to D, the ten values 1 to 0 of the translated primary digit are represented respec-

tively by the ten noted primary wires P1 to P10 extending to that frame.

At their respective contacts 2 (receiving ground over pin group 1831), the hundreds register relays 18A1 to 18A10 respectively ground the associated hundreds wires 0 to 9 in group 1833 leading to the contacts 1 to 10 of twenty-fives relays 18B23 to 18B26. For each hundreds wire 0 to 9, contacts 1 to 10 of relays 18B23 to 18B26 provide four branch extensions, one for each of the four groups of twenty lines within the concerned group of a hundred. These forty branch extensions comprise the forty P wires PA1 to PD10 over one or another of which the translated primary digit for any call is sent to the required line-link frame. The first ten of these P wires are the wires PA1 to PA10 in group 1841. They lead respectively to wires P1 to P10 extending to line-link frame A, while the second, third, and fourth groups of these P wires are wires PB, PC, and PD in groups 1842 to 1844, leading to line-link frames B, C, and D, respectively. The translated primary (or twenty-fives) digit for any translated number 111 to 055 for the line-link frames is thus determined jointly by hundreds register relays 18A1 to 18A10 in cooperation with the four twenty-fives relays 18B23 to 18B26.

IVD4b. The translated fives digit (1 to 5)

As noted, each line-link frame has a separate group of fives wires F1 to F5 extending thereto. The five values (1 to 5) of the translated fives digit are transmitted to any line-link frame over these wires, which are respective extensions of wires contained in groups 1841 to 1844. Five common fives wires 18F1 to 18F5 originate at the contacts of fives relays 18B15 and 18B16. They are connected to the fives wires of line-link frame A, B, C, or D, depending upon which of the 250's relays 18B27 to 18B30 is operated. Any such relay effect the noted connection at its contacts 1 to 5.

For any translated line number, the common fives wire 18F1 to 18F5 which becomes grounded depends jointly upon the tens digit registered and upon whether fives relay 18B15 or 18B16 is operated. The variations in the value of the translated fives digit are based on the division of any 100-line group of numbers (00 to 99) into four groups of twenty-five, and the further division of each group of twenty-five into five groups of five, as shown in the following table.

FIVES-GROUP TRANSLATION TABLE FOR ANY 100-LINE GROUP

25's	1st Five	2nd Five	3rd Five	4th Five	5th Five
1st.....	00-04	05-09	10-14	15-19	20-24
2nd.....	25-29	31-34	35-39	40-44	45-49
3rd.....	51-54	55-58	61-64	65-68	70-74
4th.....	75-79	80-84	85-88	90-94	95-99

The numbers in the body of the above table are the tens and units digits of the lines forming the successive fives groups within the group of 100. The first two tens group of lines (tens digits 0 and 1) furnish the first four fives groups in the first 25's group within the hundred, while the third tens group (tens digit 2) embraces the last five lines of the first 25's group and the first five lines in the second 25's group. The fourth and fifth tens groups (tens digits 3 and 4) furnish the last two fives groups in the second 25's group. Consequently, the value of the translated fives digit runs from 1 to 5 for the five five-line groups comprising lines 09 to 24, and starts over again with the value of 1 for lines 25 to 29, and progresses through 2 to 5 for lines 30 to 49. The translation required for the second fifty lines of the hundred is clearly a repetition of the translation required for the first fifty lines of the hundred. That is, the first and third 25's groups within the hundred each starts with two full ten-line groups and ends with the first half of the next succeeding ten-line group, while the second and

fourth 25's groups within the hundred start with the last five lines of a ten-line group and end with the next two succeeding ten-line groups.

Contacts 2 of tens register relays 18A11 to 18A20 are supplied with ground over conductor F of group 1831, and are connected to the common fives wires 18F1 to 18F5 over wires 0 to 4 in group 1834, and through contacts 1 to 5 of fives relays 18B15 and 18B16 according to the foregoing. For the first fifty lines of a hundred, wires 0 to 4 in group 1834, which are connected to contacts 2 of the first five tens relays 18A11 to 18A20, are so interconnected, as shown, with the contacts 1 to 5 of fives relays 18B15 and 18B16, that any such wire becomes connected with one or another of two of the common fives wires 18F1 to 18F5 according to which one of the fives relays 18B15 and 18B16 is operated. These same five wires 0 to 4 are employed also for the second fifty lines in the hundreds by being multiplied to the contacts 2 of the last five tens register relays 18A16 to 18A20, respectively representing called tens digits 5 to 9.

IVD4c. The translated units digit (1 to 5)

As noted, each line-link frame A to D has a separate group of units wires U1 to U5 extending thereto. The five values (1 to 5) of the translated units digit are transmitted to any line-link frame over these wires, which are respective extensions of wires in groups 1841 to 1844. Five common units wires 1837-U1 to 1837-U5 originate at the contacts 11 of units relay 18A21 to 18A30. They are connected to the units wires UA, UB, UC, or UD of line-link frame A, B, C, or D, depending upon which of the 250's relays 18B27 to 18B30 is operated.

For any translated number the common units wire grounded depends solely upon the units digit registered. The correspondence is as follows:

Registered Units Digit	Translated Units Digit
0 or 5	1
1 or 6	2
2 or 7	3
3 or 8	4
4 or 9	5

Registered units digits 0 to 4 or 5 to 9 correspond respectively to translated units digits 1 to 5. This is because the first five lines of a decimal group of ten comprise a complete group of five on a primary switch, and the last five lines of the decimal group comprise a separate complete group of five on that primary switch, or on the next one, as seen in the preceding fives-group translation table, or in Fig. 2.

In accordance with the foregoing, the first five units register relays 18A21 to 18A25, and the last five units register relays 18A26 to 18A30, at their contacts 11, respectively ground the common units wires 1837-U1 to 1837-U5.

IVD5. The called line is No. 111

If, for example, the called line is No. 111, the hundreds, tens, and units digits called are 1, 1, and 1. If so, the operated hundreds, tens, and units register relays are the second hundreds relay 18A2, the second tens relay 18A12, and the second units relay 18A22. The first fives relay 18B15 is operated by contacts 12 of relay 18A22; the first 25's relay 18B23 is operated by contacts 4 of tens relay 18A12; and the first 250's relay 18B27 is operated by contacts 4 of hundreds relay 18A2.

IVD5a. Translated primary digit 5 for frame A

Contacts 2 of the second hundreds relay 18A2 ground hundreds wire 1 in group 1833. Ground on this wire is extended through contacts 2 of the operated twenty-fives relay 18B23 to the fifth primary wire PA5 in group 1841 extending to line-link frame A.

IVD5b. Translated fives digit 3 for frame A

With the second tens relay 18A12 and the first fives relay 18B15 operated, ground through contacts 2 of relay 18A12 is extended over wire 1 of group 1834 and thence through closed contacts 3 of relay 18B15 to the third common fives wire 18F3. With the first 250's relay 18B27 operated, ground on this wire is extended through contacts 3 of relay 18B27 to fives wire FA3 in group 1841, extending to line-link frame A.

IVD5c. Translated units digit 2 for frame A

Contacts 11 of the second units relay 18A22 ground the second common units wire 1837-U2, thereby grounding the units wire UA2 of line-link frame A through contacts 7 of the first 250's relay 18B27.

By the foregoing operation, the assumed registration of line No. 111 in the block translator results in the transmission of translated number 532 to line-link frame A. This accords with Fig. 2, part 1 where the translated digit information appearing under line No. 111 is 532 at line-link frame A.

IVD6. Line-controller response

The line controller 1200 on line-link frame A responds to the primary and fives digits 5 and 3 in the translated line number by operating the associated line-controller switches 1000 and 1100 to select the indicated primary switch 800 on the frame and the indicated fives group thereon. The units relay group in the line controller 30 responds to the units digit of the translated number by selecting the indicated called line 1 in the group of five.

As described in our parent application, the line controller 1200 on the called line-link frame grounds its terminating frame wire TF, which identifies the line-link frame in the block controller, which thereupon conditions itself as described for routing the call to the identified line-link frame over an idle terminating trunk extending thereto, and for routing the call to the particular called line selected by the line-controller switches and the line 40 controller.

IVD7. Clearing out

When the operations necessary to extend the connection to the called line, if idle, have been completed, the block controller initiates the clearing-out operation described in our parent application, which includes the restoration of the operated terminating-chain relay 512 in the connected block coupler 500. Restoration of this relay removes ground from the marked hundreds, tens, units, and stations wires extending to the block translator 1800. When this occurs, the operate digit register relays of Fig. 3 restore. The other operated relays of the block translator responsively restore. The block translator is thereby cleared out, and marking ground is removed from the translated-digit wires P1 to U5 extending to the called line-link frame.

IVE. General operation for overriding translation

As previously noted, the block translator provides the following standard services by substituting overriding translation for the normal fixed translation for concerned called line numbers:

- (1) Number-transfer service.
- (2) Intercept service.
- (3) Common-number service.
- (4) 20-station code-ringing service.

IVE1. Detecting specific line numbers

Number-transfer service, intercept service, or common-number service are given depending on a specific line number being registered in the translator 1800. The setting up of that line number in the translator must be specifically detected to cause the normal fixed translation for that line number to be superseded by pre-assigned overriding translation required according to the service 75 assigned to the specific line number.

The noted detecting operation is performed by individual detector relays separately assignable to desired line numbers. The detector relays are:

- (1) 18E1 to 18E30 for number-transfer service;
- (2) 18D15, 18D18 (not shown), 18D21, and 18D24 to 18D29 for common-number service; and
- (3) 18F1 to 18F20 for intercept service.

Each detector relay has two windings, as shown, and is adjusted to operate only if both windings are energized. As described, for each detector relay, these windings are wired to separate detector terminals D1 and D2 in the common field, terminal-pin sections 1902 to 1904, Fig. 4. To prepare a detector relay to detect a specific called number, a two-conductor jumper is run from its terminal pins D1 and D2 to carry the winding terminals of the detector relay to two terminal pins in the field, section 1901 of Fig. 4. One such terminal pin is a hundreds pin in group 1 or 2 of this field, while the other is a tens and units pin in group 3 or 4 of this field. Ground appears on both such terminal pins only when a specific number is called. The concerned detector relay then operates, for both its windings are energized, each over a separate wire of the noted detector jumper. Jumpers 1951 to 1953 are three examples of the noted two-wire detector jumpers.

Hundreds relays 18A1 to 18A10, at contacts 1 respectively ground the hundreds wires H0 to H9 in group DF1. These wires extend to the detector field section 1901 and are strapped across the first ten levels respectively. These levels thus comprise hundreds detector bus bars.

Contacts 1 of tens relays 18A11 to 18A20 and contacts 1 to 10 of units relays 18A21 to 18A30 cooperate to control one hundred tens and units wires 00 to 99 in group DF2. The one which corresponds to the registered combination of tens and units digits is grounded through contacts 1 of the operated tens register relay, over the concerned wire 0 to 9 in group 1832, and a contact 1 to 10 of the operated units relay 18A21 to 18A30. These one hundred tens and units wires extend to the respective terminals in groups 3 and 4 (levels 11 to 20) of the detector field, section 1901.

Reset relay 18D3 is controlled by the detector relays to cancel the normal fixed translation and terminals in the common field are controlled by the detector relays to supply overriding translation through jumpers extending to strapped pin levels in the reset field (sections 1906 to 1909), to which conductor groups RF1 to RF4 carry a multiple of the P, F, and U wires outgoing to the line-link frames.

IVF. Number-transfer service

While the ten line links 202 of a line-link primary switch 800 are ample to provide a good busy-hour grade of service for twenty-five connected lines of more than average traffic, the ten line links serving a line-link primary switch can be overloaded during the busy hour if too many of the twenty-five connected lines are high-traffic lines.

The obvious remedy for any overloaded primary switch 800 is to change jumpers such as 201 and 209 on the M.D.F. to transfer some of its high-traffic lines to spare line locations of other line-link primary switches. Or, if enough spare line locations do not exist, low-traffic lines are transferred back to replace the transferred high-traffic lines. Such a jumper transfer, when made, divorces the transferred line from its original directory number and associates it with the one belonging to its new line-terminal location. If nothing further were done, any transferred line would require a new directory number.

Since changes in the directory numbers of working lines are bothersome to the operating company and to the subscribers, the block translator has been arranged to provide overriding translation to perform number-transfer service which enables any transferred line to retain

its original directory number. By this service, the directory number is made to follow the transferred line.

IVF1. Transfer-relay assignment

When number-transfer service is to be applied to a transferred line (to permit the noted retention of its old directory number), an available one of the thirty transfer relays 18E1 to 18E30 is assigned to the transferred line.

Referring to Fig. 2, it may be assumed that pursuant to balancing the traffic load among the primary switches on the line-link frames, line number 512 has been transferred on the main distributing frame M.D.F. to the directory-number line location 910, and that number-transfer service is to be applied to enable the transferred line to retain its original directory number. The transferred line (512) was initially served by the first primary switch on line-link frame C, third fives group, third line. Its normal fixed translation was C133. In its new location (910), line 512 is served by the seventh primary switch on line-link frame D, third fives group, first line. Its required overriding translation is therefore D731. The registration of number 512 in the block translator must therefore result in overriding translation D731.

Number-transfer relay 18E1, if available, may be assigned to transfer calls for transferred line 512 to its new location. The first column in five-level group 2 of section 1903 is assigned to relay 18E1. A two-wire detector jumper 1952 is installed to operate relay 18E1 to cancel the normal fixed translation (C133) whenever the directory line number 512 is registered in the translator, and a three-wire reset jumper 1958 is installed to provide overriding translation (D731) corresponding to the new line-terminal location of the transferred line.

IVF1a. Detector jumper 1952

The detector terminal pins D1 and D2 of the first number-transfer relay 18E1 are in column 1, levels 4 and 5 of group 2 in section 1903 of the common field, wires D1 and D2 of the two-wire detecting jumper 1952 are connected to these terminals. At the other end of the jumper 1952, its wires D1 and D2 are connected to the detector terminals for line number 512, the directory line number of the transferred line.

The hundreds digit 5 is detected by connecting wire D1 of jumper 1952 to any terminal pin in level H5 of section 1901.

The tens and units digit combination 12 is detected by connecting the wire D2 of jumper 1952 as shown to the terminal pin which is in tens level 1 and units column 2 of the detector field.

IVF1b. Reset jumper 1958

The required overriding translation (D731) is assigned to number-transfer relay 18E1 by running the three-wire reset jumper 1958 as shown between its P, F, and U pins and the required reset P, F, and U pin levels in section 1909 of the reset field. Wire P is connected to level PD7, wire F is connected to level FD3, and wire U is connected to a pin in level UD1.

The foregoing preparations adapt the block translator 1800 to provide overriding translation D731 for transferred line number 512 in substitution for its normal fixed translation (C133).

IVF2. Number-transfer operation

With the noted jumpers 1952 and 1958 installed for the first number-transfer relay 18E1, if the original directory number of transferred line 512 is called, the consequent registration of the directory-number hundreds, tens, and units digits 5, 1, and 2 in the translator causes transfer detector relay 18E1 to operate as follows:

IVF2a. Detection

Registration of hundreds digit 5 causes ground, through contacts 1 of relay 18A6, and overwire 5 of group DF1, to appear on the hundreds bus-bar level H5 of the de-

tor field (section 1901), closing a circuit over wire D1 of the attached jumper 1952, the concerned pin D1 in section 1903, and attached conductor in group CF10, for the lower winding of detector relay 18E1. At the same time, registration of tens and units digits 1 and 2 causes ground through contacts 1 of tens relay 18A12, wire 1 in group 1832, contacts 2 of relay 18A23, and wire 12 in group DF2 to appear on the tens and units terminal pin 12 in the detector field, closing a circuit over wire D2 of the connected jumper 1952 for the upper winding of the detecting number-transfer relay 18E1.

IVF2b. Resetting

Relay 18E1, which will not operate when only one winding is energized, now operates because both windings are energized. Its contacts 1 to 3 connect the associated wires P, F, and U in group CF10 to the corresponding wires in group 1804, through which number-transfer overriding translation is controlled. Wires 1804 are common to the thirty number-transfer relays 18E1 to 18E30. They comprise the normal extension of wires 1803 which originate at the open front contacts of reset relay 18D3. The predetermined overriding translation is thus withheld until the normal fixed translation has been erased.

Reset relay 18D3 is operated through contacts 4 of any relay 18E1 to 18E30. It disconnects ground from wires P, F, and U in group 1831, thereby removing ground from contacts 2 of the hundreds and tens register relays and from contacts 11 of the units register relays, thereby cancelling the normal fixed translation (C133) for the called line number 512, by removing ground from the connected primary, fives, and units wires in group 1843. Reset relay 18D3 also extends ground, over wires 1803, and through break contacts 1 to 3 of the unoperated reset relay 18D4, to the overriding common wires P, F, and U in group 1804. Resetting ground is thereby extended through contacts 1 to 3 of relay 18E1, and over wires P to U in subgroup 1 of group CF10, and their connected terminal pins, to each of the conductors in the three-wire reset jumper 1958. Ground is thereby applied to wires PD7, FD3, and UD1 in group RF4, multiplied to the corresponding wires in the frame-D group 1844. Overriding translation D731 is thus substituted for the normal fixed translation C133.

IVF2c. Line-controller response

The line controller 1200 on line-link frame C, which has no more than barely started to position the associated line-controller switches for the normal fixed translation C133, is released responsive to the described cancellation of the normal fixed translation by reset relay 18D3. The line controller 1200 on line-link frame D is activated as hereinbefore described by the overriding translated number D731.

When the overriding translation is for the same line-link frame as the cancelled normal fixed translation, the relay groups comprising digit registers in the concerned line controller clear out when relay 18D3 operates as described, and are immediately reset by the overriding translated number.

When the ensuing operations have been completed as hereinbefore described, restoration of the hundreds, tens, and units register relays of block translator 1800 restores detector relay 18E1, which restores reset relay 18D3.

IVF2d. Freeing a number-transfer relay

If a directory-number change is later made (as upon the issuance of a new directory), or if the normal turnover and reassignment of lines permits the noted transferred line 512 to be transferred back to its original switchboard location, the concerned number-transfer jumpers 1952 and 1959 are removed, freeing the associated number-transfer relay 18E1 for assignment to another transferred line.

IVG. Intercept service

As previously pointed out, number-intercept service is provided by the block translator 1800 by providing overriding intercepting translation on calls for disconnected lines or stations, to reroute such calls to an intercept operator. Up to twenty separate lines can be placed on intercept service by assigning intercept detector relays 18F1 to 18F20 respectively to them. Intercept call-in relay 18D30 is controlled by any relay 18F1 to 18F20 to call in three intercept trunks for test by the P.B.X allotter.

IVG1. Intercept-relay assignment

When number-intercept service is to be applied to a line, an available one of the twenty intercept detector relays 18F1 to 18F20 is assigned thereto, and a two-wire line-detecting jumper and a one-wire station-detecting jumper are installed as illustrated at 1953 and 1956 for the twentieth intercept-detector relay 18F20.

IVG1a. Detecting line number 959

If, for example, intercept service is to be provided for line No. 959, or for a station disconnected from that line if it is a multi-station line, intercept detector relay 18F20 if available, may be assigned to this line number.

The pin-terminal location for intercept relay 18F20 lies in the common field, section 1904, column 10, the five pins under "intercept 20." The fourth and fifth of these pins (opposite D1 and D2) are the detector terminals. A two-wire detector jumper 1953 is run from these pins to the terminal pins in the detector field representing line number 959. The first wire of the jumper detects the hundreds digit 9 when connected to a terminal pin in the level H9 of the detector field, while the second wire of the jumper detects the tens and units digits 5 and 9 when connected to the detector-field pin 9 in tens level 5 opposite the tens numeral 5 and under the units numeral 9 on the drawing. With this two-wire detector jumper installed, relay 18F20 operates subject to line number 959 being registered in the translator, as explained for number relay 18E1, jumper 1952, and line number 512.

IVG1b. Line intercept for line 959

The first three terminal pins in the group of five assigned to relay 18F20 (those in group 2 of section 1904 under the notation 20 and opposite the numeral 1, 2, and 3 on the drawing), are assignable respectively to stations which have been disconnected from a multi-station line. The wires leading to these pins are respective extensions of the wire which operates call-in relay 18D30, through respective make contacts of relay 18F20.

If line (959) to which detector relay 18F20 is assigned is an individual line, all calls thereto are to be intercepted. In this event, one of the noted terminal pins 1 to 3 is jumper-connected to ground at level 20 of the sleeve field, as shown for station jumper 1957 which is associated with set 19 of the intercept sets of terminal pins. When such a jumper is installed for intercept set 20, current flows from ground thereto over to operate intercept call-in relay 18D30 whenever relay 18F20 operates, irrespective of the registered stations digit. This operation is termed line intercept.

IVG1c. Station intercept for line 959

On the other hand, if the line (959) to which relay 18F20 has been assigned by jumper 1953 is a multi-station line from which a specific station has been disconnected, one of the station pins 1 to 3 in the said set intercept 20 is jumpered to the station bus bar corresponding to the station digit of the disconnected station. Jumper 1956 extends from terminal 1 of this set to stations bus bar ST2. The station bus bars ST0 to ST9 comprise the horizontally strapped pins in the levels terminating wires ST0 to ST9 in group CF12. These wires are grounded respectively by contacts 1 of station-

register relays 18B1 to 18B10, which record stations digits 0 to 9 respectively.

With jumpers 1953 and 1956 in place, relay 18F20 operates whenever line number 959 is registered, but without effect except when stations digit 2 is registered to ground wire ST2 in group CF12. Ground then passes over jumper 1956, wire 1 in subgroup 20 of group CG11, and contacts 1 of relay 18F20 to relay 18D30.

IVG1d. Multi-station intercept service

If two disconnected stations of the same line are on intercept service, two of the station pins 1 to 3 of the concerned group (such as intercept 20) are connected to respective station bus bars. If three disconnected stations of that line are on intercept service, all three station pins 1 to 3 are connected to respective stations bus bars.

IVG1e. More than three stations on intercept service

If more than three stations of a line are on intercept service at the same time, two or more detector-intercept relays may be assigned to the same line number to provide the required number of station-intercept pins for connection to respective stations bus bars.

IVG2. Intercept call-in

As above described intercept call-in relay 18D30 is operated from ground supplied through a contact 1 to 3 of any one of the intercept detector relays 18F1 to 18F20. Contacts 14 of relay 18D30, ground wire 1806, operating reset relay 18D4 and 18D3 in series. Reset relay 18D4 disconnects wires 1803 from wires 1804 and transfers them to wires P, F, and U of group 1865 extending to the group allotter (relays 18D5 to 18D14). Contacts 4 of relay 18D4 places battery through resistor 1802 on locking-battery wire LB of the group allotter.

Reset relay 18D3 disconnects ground from the P, F, and U wires in normal fixed translation group 1831, and extends ground through make contacts 1 to 3 of relay 18D4 to wires P, F, and U extending to the group allotter. The normal fixed translation for the called line number has thus been cancelled, and circuits are prepared for transmitting overriding translation under the control of the group allotter.

At its contacts 1 to 12 (contacts 5 to 8 not shown) intercept call-in relay 18D30 also calls in the sleeve and reset wires of group PJ, representing the three lines (011, 111, and 211) of line-link frame A which are used as intercept trunks as needed.

IVG2a. Intercept-trunk sleeve wires

As shown in Fig. 4, part 3, the sleeve wires S1 to S3 of group PJ, called in by relay 18D30, represent respective extensions of the first three sleeve wires (S1 to S3) of the thirty transfer sleeve wires S1 to S30 extending between the block translator and the previously noted sleeve bunching block (not shown) on line-link frame A. If all three of the pre-determined lines (011, 111, and 211) are in use for intercept service, all three of the noted sleeve wires S1 to S3 are jumpered on line-link frame A to the respective individual sleeve wires S of these lines. The individual sleeve wires of the three lines used as intercept trunks are thus now connected respectively to movable contact members 4, 8 (not shown), and 12 of relay 18D30. Through make contacts 4, 8, and 12 of relay 18D30, these wires S1 to S3 are connected over wires S in trunk groups 1811 to 1813 to the upper terminals of group-allotter relays 18D5 to 18D7 (18D6 not shown). The lower terminal of each group-allotter relay 18D5 to 18D14 is connected to ground through the preference lookout chain, which comprises a chain-end wire common to the ten relays and series chain contacts 5 on all of them.

IVG2b. Setting the group allotter

If all three lines used as intercept trunks are idle, relays 18D5 to 18D7 now operate from battery normally on the sleeves of the respective lines 011, 111, and 211, through their respective primary hold magnets as described in our parent application. Each such allotter relay first closes its preliminary-make contacts 4 to lock itself to locking-battery wire LB. The resulting locking circuit gives the allotter relay ample operating current and effectively shunts the associated primary hold magnet to prevent it from operating at this time.

IVG3. Overriding translation for first intercept trunk

Each noted allotter relay, at its contacts 5 locks its lower winding terminal to the associated incoming ground wire of the preference lockout chain, and opens the lockout chain to the next succeeding relay. At its contacts 6, any such relay disconnects its lower winding terminal from the end of the lockout chain. As a result, when relays 18D5 to 18D7 operate, the first relay 18D5 locks effectively and remains operated, while the succeeding relays 18D6 and 18D7 immediately restore upon being deprived of operating ground by the preferred relay 18D5. Whenever any two or more relays of the group allotter operate at the same time, the one having first position in the chain operates and locks effectively, restoring the remaining ones.

Having operated and locked effectively, allotter relay 18D5 (at its contacts 1 to 3) connects wires P, F, and U of trunk group 1811 to the wires P, F, and U of common group 1805, which are grounded as noted through contacts of relays 18D3 and 18D4. P, F, and U ground is thus extended through make contacts of call-in relay 18D30 to the reset wires P1, F3, and U2 in group PJ. As shown in Fig. 4, these reset wires are wired to the corresponding frame-A reset wires of the translator. The required overriding translated number A132 for the first intercept trunk (line 011) is thus substituted for the normal fixed translation corresponding to the number called.

IVG4. Using the second and third intercept trunks

When the first trunk of the intercept group is busy, the first group-allotter relay 18D5 fails to operate, being shunted by ground on the sleeve wire of the trunk (line 011). Then, if the second intercept trunk (line 111) is idle, relays 18D6 (not shown) operates effectively to extend P, F, and U ground over the second trunk group wires 1812 (not shown) and through contacts in group 4 to 9 (not shown) of relay 18D30 to reset wires P5, F3, and U2 in group PJ, causing overriding translated number A532 to be transmitted to extend the call to the second intercept trunk (line 111).

When the first two trunks of the intercept group are busy and the third trunk is idle, the third allotter relay 18D7 operates effectively, grounding wires P9, F3, and U2 in group PJ, through contacts 9 to 11 of relay 18D30 to send out the translated number A932 for the third intercept trunk (line 211).

IVG5. Clearing out

When the connection has been completed to the line constituting the selected trunk indicated by the overriding translated number, ground appears on the individual sleeve wire thereof, thereby shunting the concerned relay (such as 18D5) of the group allotter. The allotter relay, however, remains operated long enough to accomplish its purpose, for a short-circuited relay is slow restoring.

When the translator clears out as described, the operated intercept relay 18F20 restores, followed by the restoration of call-in relay 18D30 to restore relays 18D3 and 18D4. Contacts 4 of relay 18D4 remove locking battery from wire LB, unlocking and restoring any operated relay in the group allotter.

IVG6. All intercept trunks busy

When all three of the noted intercept trunks are busy when tested by the group allotter, no relay of the allotter operates, wherefore the cancelled normal fixed translation for the called number is not replaced by overriding translation. The block controller 1600 is thus unable to proceed with the call for the lack of a frame-identifying signal. It therefore "times out" through its cycle timer and conditions the connected block coupler 500 to return a terminating busy tone to the calling line as described in our parent application.

IVG7. Number-transfer and intercept service for the same line

Number-transfer service and number-intercept service may both be applied to the same line, as when a transferred multi-station line has been provided with number-transfer service to avoid a directory-number change, following which a station is disconnected from the transferred line. Thereupon, the directory number of the disconnected station is jumpered for intercept service as described. In that event, when the concerned line number is called, a number-transfer relay (such as 13E1) and an intercept relay (such as 18F28) both operate on detecting the called number.

If a working station on the line is called, intercept call-in relay 18D30 remains restored, and the operation of the number-transfer relay is effective to cause overriding translation to direct the call to its transferred line location. But, if the noted disconnected station is called, call-in relay 18D30 is operated as previously described, thereby operating reset relay 18D4 along with reset relays 18D3 to transfer the overriding P, F, and U ground from wires 1804 of the number-transfer relays to wires 1805 of the group allotter. The overriding number-transfer translation is thereby set aside in favor of the required intercept translation.

IVH. Common-number service

A subscriber having a group of lines (rather than only one) extending to his premises commonly desires that a common directory number be assigned to the group, and that the call be completed to any idle line of the group when the common number is called. Such lines are commonly termed trunks, particularly if they terminate at the switchboard of a private branch exchange (P.B.X) on his premises, rather than at separate telephone sets as they sometimes do.

Common-number service involves the group allotter (relays 18D5 to 18D14) and one or another of the nine relay equipments PBX1 to PBX9 (Fig. 3, parts 2 and 3), which are assignable to respective common-number groups of lines. Each ten-trunk common-number group requires a three-relay equipment such as PBX1 to PBX3, and each three-trunk common-number group requires but a single-relay equipment such as PBX4 to PBX9. A ten-trunk relay equipment (PBX1 to PBX3) can of course serve a group containing any desired number of trunks less than ten, while a three-trunk relay equipment (PBX4 to PBX9) can serve a group of two trunks or of three trunks.

The group allotter is connected with each of the ten-trunk relay equipments PBX1 to PBX3 over ten four-wire trunk sets 1811 to 1820. Each trunk set includes wires P, F, U, and S. These wires represent the translated primary, fives, and units digits, and the sleeve wire for an assigned trunk, as described for trunk sets 1811 to 1813 which are employed for intercept service as described.

The assignment of the trunk sets 1811 to 1819 to the three-trunk relay equipments PBX4 to PBX9 is such that two or three three-trunk equipments combine to serve a six-trunk group or a nine-trunk group, as required. This combining is performed by connecting the detector ter-

minals D1 and D2 of two or three three-trunk relay equipments to detect the same line number. For this purpose the trunk sets 1811 to 1819 are connected to the three-trunk relay equipments PBX4 to PBX9 progressively as given in the following table:

TRUNK-SET PROGRESSION

Relay Equipment	PBX4	PBX5	PBX6	PBX7	PBX8	PBX9
Relay No.	18D24	18D25	18D26	18D27	18D28	18D29
Trunk Sets	1811 1812 1813	1814 1815 1816	1817 1818 1819	1811 1812 1813	1814 1815 1816	1817 1818 1819

IVH1. Making up a P.B.X group

15 When a P.B.X group (or a similar common-number group) is to be made up, a call number is assigned to the group, along with the specific lines which are to serve as trunks, and an available relay equipment PBX1 to PBX9 is assigned to the group.

20 Then, from pins in the concerned group in section 1901 or group 1 of section 1902, a two-wire detector jumper is run to identify the assigned relay equipment with the assigned called number, and a sleeve jumper and a three-wire reset jumper are run for each line which is to form 25 a trunk of the group.

IVH1a. Using ten-trunk equipment P.B.X for group 000

If, for example, the call number containing hundreds, tens, and units digits 0, 0, and 0 is to be assigned to a 30 ten-trunk group to be made up, the ten-trunk relay equipment comprising relays 18D15 to 18D17 may be used if available. The terminal pins PBX1 assigned to this relay equipment comprise the first five levels (group 1) of section 1902 in the common field. The first four of these 35 levels represent the primary, fives, units, and sleeve wires (P, F, U, and S) of the respective trunks T1 to T10 to be assigned to the group. The first two terminal pins in the fifth level of this section are the detector pins D1 and D2 for the group. A two-wire jumper 1951 is run from these terminals D1 and D2 to detect line number 40 000 in the detector field. The hundreds digit 0 is detected on the hundreds levels H0, while the tens and units digit 0 and 0 are detected on pin 0 in level 0.

45 Ordinarily (though not necessarily) the specific line bearing the directory number of the common-number group forms a trunk of the group, and may, or may not, be assigned to the group as trunk 1 thereof. If, for example, line 485 is assigned as trunk 1 of the group, a three-wire reset jumper 1954 is run from the P, F, and

50 U pins of set T1 of the group to the tenth primary, the third fives, and the first units levels in the frame-B (1907) section to predetermine translated number B031 to direct the call to line 485 when the first trunk of the group is selected.

55 The sleeve pins for pin set T1 of the group is connected by a jumper 1955 to an available one of the thirty sleeve pins for frame B, such as sleeve pin S10 in the frame-B group. The corresponding sleeve pin on the sleeve bunching block (not shown) on line-link B is jumpered to the sleeve wire of the concerned line 485. In a similar manner, sleeve and reset jumpers are installed for each of the other lines which are to serve as trunks in the group.

IVH2. Calling common-number group 000

60 With jumpers installed as noted, the registration of the common-line number 000 in the translator results in the energization of both windings of detector relay 18D15 over wires D1 and D2 of jumper 1951. Relay 18D15 thereupon operates. Its contacts 13 operate relays 18D16 and 18D17, and its contacts 14 operate reset relays 18D3 and 18D4 over wire 1806.

65 Contacts 1 to 12 of relay 18D15 and contacts 1 to 14 of relays 18D16 and 18D17 connect the P, F, U, and S wires of the trunk groups 1 to 10 in wire group CF1 re-

spectively to the ten conductor sets 1811 to 1820 associated with relays 18D5 to 18D14 of the group allotter. The jumper pairs including jumpers 1954 and 1955 are thereby connected to the respective relays of the group allotter. The first relay in the group allotter which corresponds to a currently idle trunk in the connected group effectively operates and locks to battery placed on wire LB by relay 18D4 as described for number-intercept service. Any succeeding operated relays of the allotter are thereby open-circuited and restored.

With reset relays 18D4 and 18D3 operated, the normal fixed translation for the called number is cancelled, and overriding translation is effected (over a jumper such as 1954) according to the switchboard location of the first idle trunk of the group, causing the call to be directed thereto as explained for number-intercept service.

IVH2a. All common-number trunks busy

If all trunks of a called common group are busy, the allotter relay 18D5 to 18D14 all remain restored, wherefore no overriding translation is provided, although the normal fixed translation is cancelled by relay 18D4. The block controller 1600 therefore "times out" for lack of a frame identifying signal, setting the connected block coupler 500 to return a busy signal as hereinbefore noted.

IVH3. Making up three-trunk groups

The three-trunk relay equipments (relays 18D24 to 18D29) are represented by columns of terminal pins in the last five levels of (group 4) section 1902, and in the first five levels (group 1) of section 1903. When the directory-number and the make up of the lines of a three-trunk common-number group are assigned, the detector terminals D1 and D2 of an available terminal-pin group PBX4 to PBX9 are jumpered to the required points in the detector field (section 1901) to secure operation of the associated three-trunk relay (18D24 to 18D29) and the three sets of P, F, U, and S wires are jumper-connected to the required reset and sleeve terminals as described for the ten-trunk group.

IVH4. Making up six-trunk and nine-trunk groups

When a six-trunk group is to be made up, two adjacent three-trunk relays (such as 18D24 and 18D25) may be used. Both sets of associated detector pins D1 and D2 (Fig. 4) are wired to the same pins in the detector field, causing both three-trunk relays to operate when the assigned group number is registered in the translator. The six trunks of the combined group are thereupon tested as a single group of six, employing six of the trunk sets 1811 to 1819 as shown in the preceding table "Trunk-Set Progression." Similarly, a third one of the three-trunk relays 18D24 to 18D29 can be added to increase the trunk-group capacity to nine, provided the third relay selected is one which does not cause an overlap in the use of trunk sets 1811 to 1819 and corresponding relays of the group allotter.

IVJ. Twenty-station code-ringing service

As noted, when the block couplers 500 are replaced by code-ringing block couplers, the block translator 1800 provides for twenty-station code-ringing service. In the illustrated embodiment, this service is limited to the lines in the fourth fives group of any primary switch 800 on line-link frame A. When this service is applied, the block translator 1800 grounds code-control wire CC (extending therefrom to the block couplers) whenever the station called on a twenty-station line is one of the second ten stations thereon.

As described in detail in the parent application, the code-ringing block couplers are arranged normally to provide a code in accordance with the dialed stations digit for any one of the first ten stations on a line. When the translator grounds code-control wire CC, code-control

relay 2251 in the connected block coupler is operated and locked to cause a preliminary ringing signal to be sent out just before the transmission of the selected code, thereby identifying the corresponding station in the second group of ten. That is, the second ten codes are the same as the first ten codes except that each code of the second ten includes a preliminary ring.

Each twenty-station line requires two line numbers: (1) the normal line number, to which the station digit is suffixed for the first ten station codes, and (2) a second line number, to which the station digit is suffixed for the second ten stations codes on the twenty-station line. The five first line numbers and the five second line numbers for five twenty-station lines served by a primary switch 800 on line-link frame A are those normally assigned to the fourth and fifth fives group of lines on the switch. For example, referring to Fig. 2, part 1, if the first primary switch 1 on line-link frame A is assigned to twenty-station code-ringing service, the lines in the fourth fives group on this switch are the twenty-station lines. Their respective first line numbers are 015 to 019, and their respective second line numbers are 020 to 024, being the numbers normally assigned to lines occupying the fifth fives group on the primary switch.

Assigning this primary switch to twenty-station service thus effectively abolishes the five lines (020 to 024) forming the fifth fives group. Their terminals must be left vacant on the main distributing frame M.D.F. The line capacity of any line-link primary switch assigned to twenty-station service is thus reduced from twenty-five lines to twenty. Arrangements are accordingly provided to assign the primary switches of line-link frame A to twenty-station code-ringing service only as needed, thereby minimizing the reduction in line capacity to no more than the current requirements for the installation.

IVJ1. Assigning a primary switch to twenty-station service

Primary relay 18D1 of the twenty-station pair is arranged to be operated from any one of the primary wires PA1 to PA10 of line-link frame A. Wire group SF2 contains branch wires 1 to 10 corresponding to wires PA1 to PA10, and a separate isolating resistor 1801 is included in each to avoid connecting two or more wires PA1 to PA10 together when two or more primary switches are assigned to twenty-station service. The ten wires in group SF2 are extended to the respective terminal pins of level 4 of group 1 in the sleeve field, section 1905. A multiple of the wires PA1 to PA10, the primary wires for line-link frame A, comprises group 1915 extending to the respective pins in level 5 of the last-noted group in the sleeve field.

When any primary switch on line-link frame A is assigned to twenty-station service, a vertical strap 1960 is connected between the corresponding pins in the noted levels 4 and 5 of the sleeve field. The illustrated vertical straps 1960 assign primary switches 2, 3, and 4 to twenty-station service.

IVJ2. Twenty-station primary detection

With straps 1960 installed as illustrated, when a call is directed to one of the associated primary switches 2, 3, and 4 on line-link frame A, the consequent translation ground on primary wire PA2 to PA4, closes a circuit over the corresponding wire in 1915, concerned strap 1960, wire 2, 3, or 4 in group SF2, and through a resistor 1801 to primary relay 18D1. Primary relay 18D1 thereupon operates as an indication that the called line is served by a primary switch which has been assigned to twenty-station service.

IVJ3. Twenty-station fives detection

When relay 18D1 operates, it connects fives relay 18D2 of the twenty-station pair to conductor 1822, an extension of the fifth common fives wire 18F5. If the called num-

ber is one of the first twenty line numbers assigned to the concerned primary switch, one or another of the common five wires 18F1 to 18F4 is grounded, but without any special effect in the translator. But, if the called number is any one of the last five line numbers assigned to the primary switch, the fifth common fives wire 18F5 becomes grounded, operating the connected relay 18D2 over wire 1822, contacts 3 of relay 18D2, and contacts 1 of relay 18D1. The operation of relay 18D2 is an indication that the second line number of a twenty-station line has been called.

At its contacts 3, relay 18D2 locks itself to ground through contacts 1 of relay 18D1, and opens its initial operating circuit. At its break contacts 1 and 2, relay 18D2 disconnects ground from the associated wire F in group 1831, thereby cancelling the normal fixed fives translation. Front contact 2 of relay 18D2 places ground on the fourth common fives wire F4 by way of wire 1821.

By the foregoing circuit changes, relay 1802 cancels the translated fives digit 5 and substitutes the overriding fives digit 4, to transfer the call from the called line location in the fifth fives group of the primary switch to the corresponding line in the fourth fives group. For example, with the straps 1960 in place numbers A251 to A255 are changed to translated numbers A241 to A245; translated numbers A351 to A355 are changed to translated numbers A341 to A345; and translated numbers A451 to A455 are changed to translated numbers A441 to A445.

At its contacts 4, relay 18D2 grounds code-control wire CC to notify the connected block coupler that a twenty-station line has been called by the use of the second line number assigned thereto. This block coupler responsively operates as noted to cause a preliminary ring to be added to the station code to signal the corresponding station in the second group of ten instead of a station in the first group of ten on the called line.

IVJ4. Station-intercept service for twenty station lines

When the number of a station disconnected from a twenty-station line is to be placed on intercept service, the twenty-station line is treated as two separate lines, and an available intercept detector relay (18F1 to 18F20) is jumpered to detect one or the other of the line numbers of the line, as required, and a station terminal thereof is jumpered to the required station bus bar as hereinbefore described.

IVK. Divided-ringing service

Divided-ringing service, which is afforded by the block couplers is controlled by ringing-reverse wire RR extending between the block translator 1800 and the block couplers. In the illustrated example, ring-reverse wire RR is grounded by one or another of the five stations register relay 18B6 to 18B10 when any stations digit 5 to 9 is dialed, remaining ungrounded when any stations digit 0 to 4 is dialed. The ringing-reverse relay in the connected block coupler is operated by ground on wire RR, and locks as described in our parent application to cause ringing current to be sent out over the ring side R of the called line rather than over the tip side T.

IVL. Control and supervision of digit wires

Circuit difficulties within a block coupler, or at any point along the digit-wire multiple between the block couplers and the block translator 1800 may cause two of the hundreds wires H, two of the tens wires T, two of the units wires U, or two of the stations wires ST to become connected together. Unless prevented, this would cause operation of two or more relays in the concerned digit group of the block translator, and that would set up translation for another line or station in addition to the called line or called station. But, operation of two or more relays in the same digit group in the block translator is prevented by chaining the operating battery for

each digit group as explained for the line controller 1200 in our parent application.

In the hundreds relay 18A1 to 18A10, for example, contacts 3 of any relay 18A1 to 18A10, opens the associated chain, to remove operating battery from any succeeding relay of the chain. When ground appears on two or more of the associated hundreds wires H, the hundreds relay connected to the lowest numbered H wire operates normally, while the hundreds relay connected to any succeeding grounded H wire either fails to operate, or restores promptly upon having its operating battery disconnected by contacts 3 of the preferred relay in the chain.

It will be observed that the circuit arrangement still permits a call to go through, with about an even chance of reaching the desired called line, since the lower numbered one of two crossed hundreds wires should represent the correct dialed hundreds digit about half the time.

As an alarm-supervisory measure, each digit group is provided with an alarm relay (relays 18B11 to 18B14) which operates when a crossed-wire condition attempts to operate two relays in the same digit group. In the hundreds group, for example, the register relay attempting unsuccessfully to operate, finds battery through the high-resistance upper winding of alarm relay 18B11. No register relay 18A1 to 18A10 will operate, or remain operated, in series with the high-resistance upper winding of alarm relay 18B11, but relay 18B11 operates whenever a register relay attempts to draw operating battery from the disconnected end of the chain. Relay 18B11 at its contacts 1 locks its lower winding to ground through contacts of the alarm-release key 1891, part 7 of Fig. 3. The associated hundreds-alarm lamp HA becomes lighted in parallel with the locked lower winding of relay 18B11. Contacts 2 of alarm relay 18B11 grounds translator-alarm wire TR-AL (part 7 of Fig. 3) to sound an alarm by a suitable device (not shown) indicating an abnormal condition in the block translator.

The chain and alarm arrangement is similar at the tens, units, and stations relays, for which alarm relays 18B12 to 18B14 are provided, along with their associated alarm lamps TA, UA, and SA.

We claim:

1. In a block translator for translating a block of one thousand decimal line numbers into one thousand respectively equivalent non-decimal numbers, hundreds, tens, and units registers, a pair of fives relays controlled by the units register, four twenty-fives relays controlled by the tens register and the fives relays, and four two-hundred-fifties relays controlled by the hundreds register and the twenty-fives relays.
2. In a block translator for translating a block of decimal numbers into respectively equivalent line numbers, registers for the respective digits of the decimal numbers, three groups of translator relays, the relays of each group being controlled by at least one register, the relays of the second group being controlled jointly by the relays of the first group and a given register, and the relays of the third group being controlled jointly by the relays of the second group and another register.
3. In a block translator, first, second, and third groups of translator relays, first contacts on the relays of the first group controlling the relays of the second group, contacts on the relays of the second group controlling the relays of the third group, additional contacts on the relays of each group, and means including the additional contacts for effecting a number translation according to the joint setting of the relays of the three groups.
4. In a block translator as set forth in claim 3, digit registers, contacts of one register controlling the said relays of the first group, and contacts of other registers in series with said first contacts on the relays of the second and third groups.
5. In an automatic switching system including switching apparatus at which lines terminate normally in a given

fixed correspondence to their respective line numbers, a translator including apparatus for registering the respective digits of any called line numbers; means in the translator normally responsive to the registering apparatus to perform a normal fixed translation effective to indicate the terminal location of the called line, and means effective when assigned to any desired line number for cancelling the normal fixed translation thereof in favor of overriding translation effective to indicate a preassigned different terminal location of the called line.

6. In a block translator, pairs of detector-relay windings, hundreds bus bars and means for energizing them according to the value of the hundreds digit in a called number, individual detector terminals and means for energizing any one of them responsive to separate number in a group of one hundred, means for connecting one winding of any pair to any desired hundreds bus bar and for connecting the other winding thereof to any said individual terminal, and separate contact means for each said winding pair requiring concurrent energization of both windings for its operation.

7. In a block translator for providing normal fixed number translation and for providing overriding translation in place of the normal fixed translation for selected numbers, a first group of wires over which normal fixed translation is controlled, a second group of wires over which number-transfer overriding translation is controlled, and a third group of wires over which common-number overriding translation is controlled, and means for transferring effectuating potential from the wires of the first group to the wires of the second and third groups alternately.

8. In an automatic telephone system, registering means for registering a multiple digit call number, said registering means including a plurality of electric registering mechanisms one for registering each digit of the call number, electromagnetic relay means, electric control means controlled by the energization of said relay means,

5 and control circuit means for connecting said registering means with said relay means in an energizing circuit, the said control circuit means including several preparatory circuits each controlled by a registering mechanism registering its digit, completion of all said preparatory circuits completing said energizing circuit for the relay means.

9. In an automatic telephone system, registering means for registering a multiple call number, said registering means including a plurality of registering mechanisms one for registering each digit of said call number, electromagnetic relay means, electric control means controlled by the energization of said relay means, first control circuit means for connecting said registering mechanisms except one with said relay means in an energizing circuit, the said control circuit means including several preparatory circuits each controlled by one of said connected registering mechanisms registering its digit, completion of all said preparatory circuits completing said energizing circuit for the relay means, and second control circuit means controlled by the remaining one of said registering mechanisms registering its digit thereby completing the call number and controlling said control means for actuating the same when the call number is completed.
